UNITED STATES PATENT OFFICE

HANS BURMEISTER, OF BERLIN, GERMANY, ASSIGNOR, BY DIRECT AND MESNE ASSIGNMENTS, TO PYRENE-MINIMAX CORPORATION, A CORPORATION OF DELAWARE

METHOD AND APPARATUS FOR PRODUCING FIRE EXTINGUISHING FOAM

Application filed June 10, 1926, Serial No. 115,089, and in Germany July 30, 1925.

My invention relates to an improved method and apparatus for producing fire extinguishing foam briefly called firefoam.

It is already known to store the chemicals necessary for producing firefoam at the bottom of a tank below the combustible liquid and to apply to it water which causes the reaction of the chemicals and the generation of the foam when required.

In contrast herewith my method consists in storing the substances serving for the generation of the foam mixed together in a closed receptacle and generating the foam in this receptacle by applying water under pressure to the chemicals.

Particular difficulties arose in the carrying out of this method in the choice of the chemicals and in overcoming the difficulties of operation during the generation of the foam.

The difficulty in the choice of the chemicals is according to my invention eliminated by producing such chemicals which possess practically no humidity to cause a reaction between the chemicals. For example where an acid constituent such as aluminum sulfate is employed as one of the foam producing elements, it may advantageously be more or less completely dehydrated before introduction into the container wherein the foam is to be generated. This dehydrated material when mixed with dry sodium carbonate, or similar alkaline constituent, will have no tendency to cake up so long as moisture is excluded and the mixture will react readily to produce foam when water is added. It will be understood that the usual foam stabilizers, such as extract of licorice, oak bark and the like, will also be added to the mixture. To increase the safety still further such chemicals may be added to the mixture which are hygroscopic and attract and absorb the humidity penetrating into the apparatus. For example finely divided substances, such as talc, chalk, clay, pumice, starches, etc. may be added for this purpose.

An apparatus adapted for carrying out the improved method and in which the difficulties of operation during the generation of the foam has also successfully been overcome is illustrated in the drawings affixed hereto.

In Fig. 1 of the drawings the apparatus is shown in longitudinal section.

Fig. 2 is a plan view of a spray head and its spray pipes.

Referring to the drawings, *a* is a closable receptacle in which the chemicals required for the generation of the foam are stored mixed together. The water under pressure passes through a pipe *i* into the receptacle or container *a* and causes here the reaction of the chemicals upon one another and thus the generation of the foam. To bring about a uniform dissolution of the chemicals a spraying head *b* with a plurality of spray pipes *l* is provided which force the water in a strong jet and with a gyrating motion into the chemicals. The spraying head and the end of the discharge pipe *d* should be located at the lowest point of the apparatus.

When the water enters the mixture of chemicals, carbon dioxide is formed. The larger portion of the gas is detained by the foam and led away by the discharge pipe *d*. A small portion of the gas, on the other hand, fills in a short time the hollow space in the container or receptacle *a* between and above the chemicals. Since the receptacle or container *a* is firmly closed at the top, this portion of the carbon dioxide gas is unable to escape and fills during the operation of the apparatus the entire space down to the approximate level of the lower end of the pipe *d*. In this way the result is attained that the chemicals in the receptacle or container *a* remain during the operation permanently dry above the lowest end of the pipe *d*. Owing to this dry storage the internal resistance of the chemicals against the foam generated becomes so low that the chemicals sink continuously and uniformly down towards the bottom.

It is obvious that due to this gas separation and storage only a very small space of the container *a* is wetted by the water and shows only minute remainders of foam or humidity when the apparatus is stopped.

Owing to this development of gas the apparatus may be so constructed that it may be recharged while in operation. For this purpose the apparatus has been subdivided

and possesses an upper chamber or compartment *n* which is adapted to be closed in an airtight manner from outside by means of a flap *o*. *k* is an airtight cover through which the chemicals are charged into the upper chamber. For the purpose of balancing the pressure in the lower and the upper compartment, a connecting pipe *q* with stopping device *r* is provided. As soon as the contents of the upper chamber *n* has been emptied into the lower, the flap *o* is closed as well as the valve *r* or the like. The cover *k* can now be opened and fresh chemicals may be introduced into the apparatus through it.

15 After closure of the cover *k* the stop valve *r* is opened so that fresh carbon dioxide gas passes from the lower chamber into the upper chamber *n*. Then the flap door *o* is opened so that the chemicals are able to flow along 20 the walls of the funnel *p* into the lower chamber. Below the flapdoor *o* is provided a distributor *s* for the chemicals dropping down from the funnel.

c is a nozzle which may either serve to 25 dilute the mixture produced by additional water or as jet nozzle in conjunction with an ejector *m* for sucking up the mixture produced from the receptacle or container *a*. *d* is the discharge pipe for the foam.

30 In special cases and particularly with large apparatus where large inner and outer resistances have to be dealt with, a by-pass *e* may preferably be provided which in the drawings is shown outside the apparatus, 35 but which may equally well be arranged inside the receptacle or container. By this by-pass fresh water is discharged from the outlet pipe *f* on to the stored chemicals. In this manner a reaction of the chemicals at 40 the top of the apparatus is attained in a short time. By the gas and foam generation a pressure is set up here, which, however, is not greater than the pressure of the water in the mains. By this arrangement a difference of pressure is set up in the upper part 45 of the apparatus and at the level of the discharge pipe at the spray nozzle *c*. The excess pressure prevailing in the upper part of the apparatus has the effect that the chemicals stored in the dry state are continuously 50 fed towards the bottom of the apparatus which ensures a uniform generation of foam.

h is an additional water nozzle in the foam withdrawing pipe to enable the viscosity of 55 the foam to be controlled as desired. If the nozzle *c* is so dimensioned that with the valve *g* closed a foam as tough and thick as possible is generated, the quality of the foam may be changed by opening the valve *g* more or less, so that by the introduction of additional water into the foam discharge pipe the foam 60 can be made as thin as desired.

It will be understood by those skilled in 65 the art that various modifications may be made in the method and apparatus without

departing from the spirit and scope of my invention and all such modifications are intended to be covered by the following claims.

I claim as my invention:—

1. The method of producing foam, more 70 particularly for fire extinguishing purposes, which consists in storing the substances serving for the generation of the foam mixed together in a closable container, introducing water continuously under line pressure into said container to produce the fire foam in said container, and discharging the foam from said container under line pressure and the gas pressure developed within said container.

2. The method of producing foam, more 75 particularly for fire extinguishing purposes, which consists in storing in a closable container a mixture of foam-producing substances which possesses practically no moisture, introducing water under line pressure into said container at a definite point, gradually bringing the mixture and water together at said point, whereby said water will react with only a portion of said mixture at 80 a time, and removing the foam produced by the reaction under pressure.

3. The method of producing foam, more 85 particularly for fire extinguishing purposes, which consists in storing in a closable container a mixture of foam-producing substances which possesses practically no moisture and a moisture-absorbing constituent, introducing water under line pressure into said container at a definite point to react with 90 only a portion of said mixture at a time as they are gradually brought together, and removing the foam produced by the reaction under pressure.

4. In an apparatus for producing fire foam, 95 a closed receptacle in which the chemicals required for the generation of the foam uniformly mixed are stored in the dry state, a pipe opening into said receptacle adapted to be connected to a line carrying water under pressure, means connected with said pipe for 100 distributing the water over a limited portion of said chemicals thus to produce said foam, and an outlet adjacent said means to discharge the foam.

5. In an apparatus for producing fire foam, 105 a closed receptacle in which the chemicals required for the generation of the foam uniformly mixed are stored in the dry state and a pipe opening into said receptacle for adding water under pressure to said chemicals 110 and thus to produce the said foam, an outlet for foam adjacent said pipe, a closable chamber in communication with said receptacle adapted to permit the recharging of 115 said apparatus during service, and means for equalizing the pressures in said receptacle and chamber.

6. In an apparatus for producing fire foam, 120 a closed receptacle in which the chemicals required for the generation of foam are stored 125

uniformly mixed in a dry state, a pipe opening into said receptacle for adding water under pressure to said chemicals to produce foam, said receptacle comprising an upper chamber and a lower chamber to permit recharging of the apparatus during service and a by-pass arranged to connect the upper part of the upper chamber with the lower chamber to balance the pressures to facilitate feed of recharging chemicals from the upper chamber to the lower chamber.

7. Apparatus for producing foam for fire extinguishing purposes comprising a container for uniformly mixed foam forming chemicals, a discharge conduit for foam leading from said container, said conduit having an intake opening directed away from the center of said container, an inlet for water within said container terminating in a nozzle 20 alined with an opening in said conduit and arranged to act as an ejector.

8. Apparatus for producing foam for fire extinguishing purposes comprising a container for uniformly mixed foam forming chemicals, an outlet means for foam leading upward within said container from a point adjacent its bottom to a point of use, and means adjacent the bottom of said container arranged to direct a jet of water over a local 30 area at the bottom of the container and another jet of water into the foam outlet.

9. Apparatus for producing foam for fire extinguishing purposes comprising a container for uniformly mixed foam forming chemicals, a discharge conduit for foam leading from said container, a plurality of nozzles arranged to direct jets of water into said container adjacent the bottom of the charge of chemicals therein and an opening in said conduit alined with one of said nozzles together with an inlet at the top of said container to admit water above said foam forming chemicals.

10. Apparatus for producing foam for fire extinguishing purposes comprising a container for uniformly mixed foam forming chemicals, a discharge pipe for foam extending from near the bottom of said container upwardly and having a restricted portion, 50 and a nozzle alined with said discharge pipe and cooperating with the restricted portion to form an ejector.

11. Apparatus for producing foam for fire extinguishing purposes comprising a container for uniformly mixed foam forming chemicals, a discharge pipe for foam extending from near the bottom of said container upwardly and having a restricted portion, a nozzle alined with said discharge pipe and cooperating with the restricted portion to form an ejector, and a plurality of nozzles surrounding the first mentioned nozzle.

12. Apparatus for producing foam for fire extinguishing purposes comprising a container for uniformly mixed foam forming

chemicals, a discharge pipe for foam extending from near the bottom of said container, a nozzle alined with said discharge pipe and cooperating therewith to form an ejector and means for admitting water directly to said discharge pipe, substantially beyond said nozzle.

13. Apparatus for producing foam for fire extinguishing purposes comprising a stationary upright container for a charge of uniformly mixed foam forming chemicals, an outlet pipe for foam leading upwardly from a point spaced from but relatively near the bottom of said container and having a restricted portion, an upwardly directed nozzle alined with said outlet pipe and cooperating with the restricted portion to form an ejector, and an auxiliary nozzle to direct a stream of water into the charge of foam forming chemicals.

14. Apparatus for producing foam for fire extinguishing purposes comprising a stationary container for a charge of uniformly mixed foam forming chemicals, an outlet pipe for foam having its intake spaced from but near the bottom of said container and facing the same, a nozzle directed upwardly into said outlet pipe, the nozzle and outlet pipe being formed to constitute an ejector, and an auxiliary nozzle adjacent the bottom of the container and adjacent the intake to said outlet for directing a stream of water into the bottom portion of the charge of foam forming chemicals.

15. Apparatus for producing foam for fire extinguishing purposes comprising a stationary container for a charge of uniformly mixed foam forming chemicals, an outlet pipe for foam extending from a point near the bottom of said container, and having its intake opening directed away from the main body of said charge, a nozzle alined with said outlet pipe, the outlet pipe and nozzle being formed to constitute an ejector, and an auxiliary inlet for leading water to said container at a point near the top of said charge.

16. The method of producing foam, more particularly for fire extinguishing purposes, which consists in storing in a closable container a mixture of foam-producing substances, introducing water under line pressure into said container near its bottom, gradually feeding the mixture into the water so that the latter will react with only a portion of said mixture at a time, and removing the foam produced by the reaction under pressure.

17. The method of producing foam, more particularly for fire extinguishing purposes, which consists in storing in a closable container a mixture of foam-producing substances which possesses practically no moisture, introducing water under line pressure into said container to react with only a portion of said mixture at a time, and remov-

ing the foam produced by the reaction under the pressure produced by the reaction assisted by the movement of water under line pressure.

18. In an apparatus for producing fire foam a closable container adapted to receive a mixture of foam forming chemicals, a series of jets at the bottom of said container adapted to direct water into the bottom portion of said mixture, means for connecting said jets to a water line, means for removing the foam as it is developed at the bottom of said container, said means comprising a duct leading upward through said container to a point of use and means for directing water from said line into said foam removing means.

19. In an apparatus for producing fire foam a closable container adapted to receive a mixture of foam forming chemicals, a series of jets at the bottom of said container adapted to direct water into the bottom portion of said mixture, means for directing water into said container adjacent the top, an outlet adjacent the bottom of the container for the removal of the foam developed, means for directing water into said outlet to assist in the removal of the foam, and means adapted to be connected at a single point to a water line for delivering water to said jets and to the two mentioned water directing means.

In testimony whereof I affix my signature.
